UNITED STATES PATENT OFFICE.

EUGENE A. CROWE, OF BROOKLYN, NEW YORK, ASSIGNOR TO THE E. S. HIGGINS CARPET COMPANY, OF NEW YORK, N. Y.

DESIGN FOR CARPET.

SPECIFICATION forming part of Design No. 28,280, dated February 8, 1898.

Application filed January 3, 1898. Serial No. 685,499. Term of patent 3½ years.

To all whom it may concern:

Be it known that I, EUGENE A. CROWE, a citizen of the United States, residing at Brooklyn, in the county of Kings and State of New York, have invented and produced a new and original Design for Carpets, of which the following is a specification, reference being had to the accompanying drawing, forming a part thereof, which represents a face view of a carpet in which my new design is embodied.

The invention relates to a design to be worked into or upon surfaces, such as carpets and similar fabrics; and it consists of the novel conformation of the figures, as herein shown and claimed.

An irregular checkered background is produced, upon which the main figure A appears,

of which the figures a , a' , a^2 , and a^3 are repeats. The main figure represents a branch with leaves thereon, the leaves apparently resting upon other larger and shadowy leaves. Small branches B, provided with leaves, are arranged between the larger main branches A, their leaves also appearing upon shadowy duplicates, and between the main and minor branches fanciful scrolls and clusters of flowers are arranged.

I claim—

The design for carpet, substantially as shown.

EUGENE A. CROWE.
